United States Patent Office

Des. 180,435

Patented June 11, 1957

180,435

VEHICLE ORNAMENT

Philip C. Auren, Worcester, Mass.

Application June 15, 1956, Serial No. 41,901

Term of patent 3½ years

(Cl. D14—18)

The single figure is a perspective view of a vehicle ornament, showing my new design.

No references cited.

I claim:

The ornamental design for a vehicle ornament, as shown.
